HIGHWAY CROSSING PROTECTION

Edwin J. Schaefer, Wilmington, N. C., assignor to
The Union Switch & Signal Company, Swiss-
vale, Pa., a corporation of Pennsylvania

Application July 9, 1936, Serial No. 89,722

9 Claims. (Cl. 246—130)

My invention relates to highway crossing protection, that is, to apparatus for protecting the intersections of railways and highways.

I will describe three forms of apparatus embodying my invention, and will then point out the novel features thereof in claims.

In the accompanying drawing, Fig. 1 is a dia-
grammatic view showing one form of apparatus
embodying my invention. Figs. 2 and 3 are dia-
grammatic views showing modified forms of the
apparatus of Fig. 1, and also embodying my in-
vention.

Similar reference characters refer to similar
parts in each of the views.

15 Referring first to Fig. 1, the reference charac-
ters 1 and 1a designate the track rails of a rail-
way over which traffic moves in both directions.
These rails are divided by insulated joints 2 to
form two track circuit sections having, normally,
20 an effective length defined by the distance D—E
and F—G. These track circuits, at times, have
an effective length D—F and E—G, respectively,
as will be explained hereinafter. A highway H
intersects the railway track between the rail
25 joints at E and F.

The left-hand section of track is provided with
a track circuit comprising a source of current 3
and the winding of a track relay TR1. This cir-
cuit may be traced from the positive terminal of
30 source 3 at location D, through rail 1, wires 4
and 5, winding of relay TR1, wire 6, front contact
7—8 of relay XR2, wire 42, and rail 1a, to the
negative terminal of source 3. The right-hand
35 section of track is provided with a similar track
circuit including a second source 3 at location G
and the winding of the track relay TR2. This
circuit may be traced from the positive terminal
of source 3, through rail 1, wire 10, front contact
40 11—12 of relay XR1, wire 13, winding of relay
TR2, wires 14 and 15, and rail 1a, back to the
negative terminal of source 3.

45 Relay XR, which comprises the right-hand
and left-hand magnets XR2 and XR1, is the usual
interlocking relay and may be of any suitable
type, such, for example, as the relay shown in
United States Letters Patent No. 1,799,629, granted
to W. K. Lockhart and T. J. O'Meara, on April
7, 1931. This type of relay is well known and is
characterized by the fact that when the left-hand
50 magnet XR1 is deenergized, the downward
movement of the armature associated therewith
operates a mechanical locking device which keeps
the armature associated with the right-hand
magnet XR2 "locked up" in approximately its
55 mid-position, whereby the back contacts 7—9

and 16—17 remain open. Similarly, if the right-
hand magnet XR2 is the first to become deener-
gized, then back contacts 11—13 and 18—19 are
prevented from closing, even though magnet
XR1 becomes subsequently deenergized. Front
5 contacts 7—8 and 11—12 have, what I shall term,
the "flagman" adjustment. That is, these con-
tacts remain closed when the associated ar-
mature is in the "locked up" position. The inter-
locking relay XR controls a highway crossing sig-
10 nal S which may be of any suitable type but
which, as here shown, is a bell. Signal S be-
comes energized over an obvious circuit whenever
either back contact 16—17 or 18—19 becomes
closed.

15 Assuming that a train moving toward the right
enters the detector section D—E, the shunt across
the rails due to wheels and axles of the train de-
energizes relay TR1, causing front contact 20
to open and thus to deenergize magnet XR1 20
of the interlocking relay. Front contact 11—12
opens because the associated armature assumes
its fully released position. It should be noted that
the opening of front contact 11—12 opens the
circuit for relay TR2 which thereupon releases, 25
and, in turn, opens the circuit for magnet XR2
at front contact 21. The "flagman" contact 7—8
of magnet XR2 will not open, however, and the
back contacts 7—9 and 16—17 will not close
because of the interlocking feature referred to 30
above. The back contact 18—19 will close, thus
completing the circuit for signal S which now
provides an indication at the crossing of the ap-
proach of the train.

35 The closing of back contact 11—13 closes a
shunt around the rail joint 2 at location E where-
by the train shunt remains effective in preventing
the pick-up of relay TR1, and, consequently, the
pick-up of relay XR1, until the train passes be-
yond the rail joint at location F. This insures
40 that the warning device at the crossing will re-
main in operation until the rear end of the train
completely clears the crossing.

When the train completely clears section D—F,
45 the energizing circuit for relay TR1 will again
become effective. This circuit has already been
traced and includes source 3 at location D, wires
4, 5, and 6, and "flagman" contact 7—8 of relay
XR2. The reason for maintaining front contact
7—8 closed in spite of the deenergized condition
50 of the magnet XR2 will now become apparent,
since the closed condition of this contact makes
it possible to pick up the rear track relay after
the train clears the crossing. The pick-up of
relay TR causes relay XR1 to pick up over con- 55

tact 20, which latter relay prepares a pick-up circuit for relay TR2 at contact 11-12. As soon as the train completely clears section F-G, relay TR2 becomes energized from source 3 at location 5 G, over the circuit previously traced for this relay. The closing of contact 21 of relay TR2 causes relay XR2 to become energized. The apparatus is now restored to the normal condition in which it is illustrated in the drawing.

10 The sequence of operation for a train approaching the crossing in the reverse direction, that is, from right to left, is similar to that described above, and need not be repeated in detail. It will be sufficient to state that relay TR2 will first release, followed by relays XR2 and TR1. Relay XR1 will then be deenergized but its "flagman" contact 11-12 will remain closed and its back contact 11-13 will remain open due to the locking feature which was brought into play by the 15 prior release of relay XR2.

15 Referring now to Fig. 2, the apparatus of this figure functions in a similar manner to that described in connection with Fig. 1, but it will be noted that, in Fig. 2, relays TR1 and TR2 are 20 eliminated and the interlocking relay XR itself performs the functions of the track relays. A further difference is that instead of opening the circuit of the forward relay upon shunting of the rear relay due to the entry of a train into the detector section, the rear relay causes a shunt to be 25 applied across the forward relay.

25 Normally, with the section D-G unoccupied, both relays XR1 and XR2 are energized. The circuit for relay XR1 includes source 3 at location 30 D, rail 1, wire 22, winding of relay XR1, wires 23 and 24, and rail 1a, back to the source 3. A similar circuit for relay XR2 includes source 3 at location G, and wires 25, 26, and 27.

30 When a train moving toward the right enters 40 the detector section D-E, relay XR1 will release due to the train shunt and will initiate the warning at the crossing due to the closing of its back contact 18-19. The closing of back contact 11-13 places a shunt around the rail joint 45 at location E, as in Fig. 1, to extend the length of the track circuit so as to include the highway and thus to insure that relay XR1 will not pick up until the train fully clears the crossing. Furthermore, the closing of back contact 28 closes an 50 obvious shunt path around the winding of relay XR2 whereby this relay is deprived of energy. The back contacts of relay XR2 will not close, however, and the "flagman" contact 29-30 will 55 not open because of the locking feature. Therefore, the auxiliary shunt path around relay XR2 will remain effective, over contact 29-30, until such time as relay XR1 picks up. This will occur when the rear end of the train passes location F.

60 When this happens, the train shunt will be removed from the track circuit section D-F and relay XR1 will receive energy over its previously 65 traced energizing circuit. Thereupon, the warning will be discontinued and the auxiliary shunt will be removed from around relay XR2. As soon as the train completely clears section F-G, relay XR2 will pick up over its obvious energizing circuit, whereupon the apparatus will be restored to its normal condition. The operation for a 70 train movement from right to left will be obvious from the foregoing description.

75 The auxiliary shunt path for magnet XR2 insures that when a light engine passes rapidly from track section D-E to track section F-G, magnet XR2 will become deenergized before mag-

net XR1 becomes energized, thus insuring that the interlocking feature of relay XR will function properly.

It should be noted in connection with Fig. 2 that should both relays XR1 and XR2 release 5 simultaneously, for any reason, an inoperative failure of the highway crossing apparatus will not result because, as soon as normal conditions are reestablished in the section, relays XR1 and XR2 10 will pick up again. In Fig. 1, on the other hand, the simultaneous release of relays XR1 and XR2 15 might cause both relays TR1 and TR2 to release, whereupon relays XR1 and XR2 would both remain released and would not restore themselves automatically to the normal or picked up position. 15

Referring now to Fig. 3, the apparatus of this figure is similar to that of Fig. 2 but comprises a slightly modified circuit arrangement which, however, provides substantially the same type of protection as is provided by the apparatus of 20 Fig. 2. In Fig. 3, when a train enters the detector section D-E from the left, relay XR1 releases and closes a shunt path around the rail joint at E over wire 31, back contact 32, wires 33 and 34, "flagman" contact 35-36, and wires 37 25 and 38. A shunt is also placed around the winding of relay XR2, as in Fig. 2, over wire 39, back contact 40, wires 41 and 34, "flagman" contact 35-36, and wire 31. It will be apparent, therefore, that in Fig. 3, the various operations and 30 their sequence are similar to those previously described for Fig. 2. Consequently, the operation of the apparatus will be clear without further detailed explanation.

35 From the foregoing description, it will be apparent that I have provided highway crossing protection involving a minimum of apparatus, yet providing a high degree of safety and reliability in its operation.

Although I have herein shown and described 40 only three forms of apparatus embodying my invention, it is understood that various changes and modifications may be made therein within the scope of the appended claims without departing from the spirit and scope of my invention. 45

Having thus described my invention, what I claim is:

1. In combination with a section of railway track intersected by a highway, two track circuits for said section, one at either side of the highway, an interlocking relay having two magnets controlled by traffic conditions in said two track circuits respectively, means controlled by one of said two magnets effective when the track circuit associated therewith is occupied for extending said associated track circuit to include the highway, and means including a flagman contact of said other magnet effective during the 60 occupancy of said associated track circuit for deenergizing the other magnet of said interlocking relay.

2. In combination with a section of railway track intersected by a highway, two detector 65 track circuits one for either direction of traffic over said section, an interlocking relay having two normally energized magnets which become deenergized due to traffic entering the associated detector track circuit respectively, and a shunt 70 circuit for each magnet including a flagman contact of such magnet and effective when the other magnet is deenergized for insuring the release of the magnet associated with the detector track circuit in advance and for avoiding an inopera- 75

tive condition of said interlocking relay in the event that both of said two magnets release simultaneously.

3. In combination with a section of railway track intersected by a highway, two track circuits for said section, one at either side of the highway, an interlocking relay having two magnets receiving energy from said two track circuits respectively, means controlled by one of said magnets for at times extending the track circuit associated therewith to include the highway, and means governed by said one magnet and including a front contact of the other magnet for at times controlling the energization of the other of said magnets.

4. In combination with a section of railway track intersected by a highway, two track circuits for said section, one at either side of the highway, an interlocking relay having two magnets receiving energy from said two track circuits respectively, and means effective when one of said magnets is deenergized by the entry of a train into its associated track circuit for controlling the length of said associated track circuit and for closing a shunt path around the other of said two magnets over a front contact of said other magnet.

5. In combination with a section of railway track intersected by a highway, two track circuits for said section, one at either side of the highway, an interlocking relay having two magnets receiving energy from said two track circuits respectively, means including a back contact of one of said magnets for extending the track circuit associated with such magnet to include the highway, and means including a back contact of said one magnet and a front contact of the other of said magnets for closing a shunt path around said other magnet.

40 6. In combination with a section of railway track intersected by a highway, two track circuits for said section, one at either side of the highway, a track relay for each of said two track circuits, an interlocking relay, circuits for energizing one and the other magnet of said interlocking relay controlled respectively by one or the other of said track relays, means controlled by one magnet of said interlocking relay for extending the associated track circuit to include

45 the highway, and means including a flagman con-

tact of said one magnet for controlling the energization of said other track relay.

7. In combination with a section of railway track intersected by a highway, two track circuits for said section, one at either side of the highway, a track relay for each of said two track circuits, an interlocking relay, circuits for energizing one and the other magnet of said interlocking relay controlled respectively by one or the other of said track relays, means for energizing said one track relay from its associated track circuit including a flagman contact of said other magnet of the interlocking relay, means for energizing said other track relay from the track circuit associated therewith including a flagman contact of said one magnet of the interlocking relay, and means controlled by said one magnet for extending the associated track circuit to include said highway.

8. In combination with a section of railway track intersected by a highway, two track circuits for said section, one at either side of the highway, an interlocking relay, a track relay for each of said two track circuits and energized over a flagman contact of one and the other magnet respectively of said interlocking relay, circuits for energizing one and the other magnet of said interlocking relay each including a front contact of the respective track relay, and means including a back contact of one or the other of said two magnets for extending the associated track circuit to include said highway.

9. In combination with a section of railway track intersected by a highway, two track circuits for said section, one at either side of the highway and each terminated by a rail joint near the highway intersection, an interlocking relay having its two magnets controlled respectively by traffic conditions in said two track circuits, means including a back contact of one of said magnets and effective when the associated track circuit is occupied for closing a shunt path around one of said rail joints to thereby extend said associated track circuit to include the highway, and means including a flagman contact of said one magnet for controlling the track circuit associated with the other magnet to thereby modify the control of the other of said magnets by its associated track circuit.

EDWIN J. SCHAEFER. 50
